UNITED STATES PATENT OFFICE.

ALFRED MAYHEW, OF LONDON, COUNTY OF MIDDLESEX, ENGLAND.

AUTOMATIC BOILER-FEEDER.

SPECIFICATION forming part of Letters Patent No. 364,534, dated June 7, 1887.

Application filed July 29, 1886. Serial No. 200,437. (No model.) Patented in France April 8, 1884, No. 161,404; in Belgium May 10, 1884, No. 65,124; in England May 13, 1884, No. 7,647; in Germany May 20, 1884, No. 30,639; in Canada December 13, 1884, No. 20,730; in India in 1885, No. 1; in Austria-Hungary March 22, 1885, No. 44,658 and No. 15,285, and in Italy December 31, 1885, No. 1,485.

To all whom it may concern:

Be it known that I, ALFRED MAYHEW, a subject of the Queen of Great Britain and Ireland, and a resident of No. 3 Victoria street, 5 Westminster, London, in the county of Middlesex, England, engineer, have invented certain Improvements in Automatic Boiler-Feeders, (for which I have obtained a British patent, No. 7,647, dated May 13, 1884; a French patent, No. 161,404, dated April 8, 1884; a Belgian patent, No. 65,124^b, dated May 10, 1884; a German patent, No. 30,639, dated May 20, 1884; an Italian patent, No. 1,485, dated December 31, 1885; an Austro-Hungarian patent, 15 No. 44,658 and No. 15,285, dated March 22, 1885; a Canadian patent, No. 20,730, dated December 13, 1884, and an East India patent, No. 1, dated 1885,) of which the following is a specification.

20 My invention relates to improvements in automatic boiler-feeders.

The objects of my improvements are, first, to provide an absolutely automatic feeder which, after being started, will continue to feed 25 water to the boiler in such quantity only as is required to maintain a constant working-level so long as evaporation continues, thus preventing all the expansion and contraction arising from irregular feeding, and when the evaporation ceases will automatically stop itself; 30 second, to provide an automatic feeder which has only the simplest form of working parts least liable to get out of order and requiring the minimum of attention, cleaning, oiling, 35 and packing, and which will sound an alarm at once if, from any cause, it should fail to act or should the supply of feed-water fail; and, third, to feed water at a higher temperature than heretofore. I attain these objects by the apparatus illustrated in the accompanying drawings, in which—

40 Figure 1 is a vertical section through an entire feeder. Fig. 2 is an elevation of a feeder and its connections to a single boiler.

45 Similar letters refer to similar parts throughout the figures.

The apparatus consists of a cylindrical copper vessel, A, the upper end of which is reduced in diameter and fitted with a casting

provided with a vertical passage, a, having a 50 right-angle branch, a', leading to the upper side of a single-acting steam-valve, B. This valve is preferably of the miter type, closing at its upper end, and carries a weight, b, upon its upper end when in its seat, as shown in Fig. 55 1. This weight b is calculated in proportion to the area of the valve-seat, so that the valve B may fall from its seat when the pressure is equalized on both sides. The valve B is enclosed in a casing, b', recessed into the casting 60 in which its seat is formed, and in some cases a ring, b², is formed around the valve, between which and the casing b' a clearance-space, b³, is left for the passage of steam at low velocity. This ring b² is employed for convenience of 65 fitting and adjusting the diameter of the valve, and also to act as a guide for the steam-valve B. Its area may be calculated, if desired, so that when the required velocity of steam is attained its pressure on the said area will actuate the valve; but this is not essential, as the same purpose may be effected by making the diameter of the weight b the same as the diameter of the ring b²—that is, rather less than the diameter of the valve-casing.

70 A steam-pipe, C, from the steam-space of the boiler communicates with the under side of valve B. At the upper end of passage a a chamber, a², is formed, above which is placed a casing, D, containing an ordinary copper 75 float, d. The float d is fitted with pin-valves d' and d² at its top and bottom, respectively. The upper valve, d', controls an air-escape aperture, d⁴, and the lower one, d², controls an air-inlet aperture, d⁵.

In the chamber a² aforesaid, below the air-valve casing D, the head of a pipe, E, is placed. This pipe is capable of vertical reciprocating motion, which motion is determined by the length of a slot, e, formed as shown, working 80 over the fixed pin e'. A contraction, a³, is formed between the chamber a² and the passage a aforesaid, through which the pipe E projects down and fits loosely in the passage a, and two slots, e² e³, are provided near the 85 lower extremity. Within the pipe E the moving spindle F is fitted concentrically and loosely, having an annular clearance-space left

between its exterior surface and the interior surface of E. It is held in position by a rivet, f, near the base of E.

The copper vessel A is provided near its lower extremity with a flange, a³, which rests on and is fixed to the base-casting by a flange or in suitable manner, and the lower extremity of A terminates in an enlarged chamber, G, formed therein. The suction and delivery pipes H K communicate with the chamber and are fitted with valves h k. A partition, g, is formed across the casting, which forms the base of the chamber G and also the top of a lower chamber, L, which is connected direct to the water in the boiler by a pipe, l, which is led into the delivery-pipe. In the partition g an injection-valve, M, is fitted, working in a gun-metal casing, m. The top of m is formed of a hexagonal shape, and any convenient number (say six) of apertures, m', are drilled in it. An ascending pipe, m², is attached to the upper part of m above these holes. The valve M is fitted with a perforated pipe, m³, extending downward into chamber L. A hole, m⁴, is drilled through the center of M, in which a moving spindle, N, works vertically, and the lower end of this spindle terminates in a head, n, which, when it is in the lowest position, rests on a projection, l', formed on the casting at the base of chamber L.

The feeder may be placed in any convenient situation near the boiler, but above working-level, and its connections thereto may be arranged advantageously, as shown in Fig. 2.

The steam-pipe C, projecting a suitable distance, say six inches, into the steam-space of the boiler, leads, as described, to the under side of valve B. A branch pipe, c, is taken off C, leading to the top of a branch formed on the delivery-pipe K, and a pet cock may be fixed at the junction. Stop-cocks c³ c⁴ are fitted on C and c, as shown. The lower part, C', of C passes concentrically into and down K to or about to the working-level of the water in the boiler. The delivery-pipe leads to a check-valve, P, which is provided with a small hole, p', controlled by a spindle and hand-wheel, p². The upper end of the delivery-pipe K is constructed preferably with a trap-bend, such as p, upon which a petcock may be fixed, and from which also a branch pipe, q, is carried up, to the top of which an alarm-whistle, Q, is attached. This alarm-whistle contains a fusible plug which will melt at a temperature of about 200° Fahrenheit, or near the boiling-point. This alarm-whistle may be attached to the feeder itself, or to any suitable part of the connections.

In order to start the apparatus, all valves being closed, the air-valve and its casing D are removed and the whole apparatus and its pipes filled with water, which can be tested by the various petcocks. D is then replaced, and the hole p' in the check-valve P opened to allow a certain quantity of water to pass from the boiler into the feeder and its pipes to establish boiler-pressure uniformly therein.

The operation of the apparatus is then as follows: On opening the stop-valve on steam-pipe C, the steam passing through the clearance-space b³ follows the water past steam-valve B down along passages a' and a and vessel A, equalizing the pressure on the surface of water in A, and allowing said water to fall by gravity into the boiler through the delivery-pipe K and check-valve P. When the steam reaches the base of A and enters the enlarged chamber E, a sudden expansion takes place, which causes a greater velocity of steam through the pipe C between the weight b (or the ring b², when employed,) and casing b' of the steam-valve B. The clearance-space b³ is calculated and made of just sufficient size to allow the steam to pass only at a certain velocity. When the extra velocity aforesaid takes place, the calculated velocity is exceeded. The additional pressure therefore acts on the surface of the weight b (or the area of the ring b², when employed) and lifts the steam-valve B against its seat, thus shutting off steam from the whole apparatus. Then the pressure in A at once falls below the boiler-pressure and a certain quantity of water from chamber L is forced up (by the constant boiler-pressure therein) through injection-valve M and ascending pipe m². This water, coming among the steam then contained in A, condenses it at once, creating vacuum. The effects of this vacuum are twofold: First it causes a charge of water to be drawn through suction-valve H, which is adjusted to allow of any desired velocity of inflow of water into chamber G. Part of this water (being at a lower temperature than that contained in chamber L) passes through the holes m' in m at each action of the feeder up the ascension pipe, and assists condensation, as described, in A. A second effect of the vacuum is to cause the water contained in chamber a² to be sucked down the clearance-space surrounding pipe E at the contraction a'. This action has the effect of lifting spindle F first up to pin e', it being lighter in proportion to its area than the pipe E. As the vacuum increases in proportion to the area and weight of pipe E, it also is raised until the base of the slot e takes against the pin e'. When the apparatus has drawn its full charge of water and the pressure is thereby equalized, as described, the pipe E falls and is followed by spindle F, and this quadruple movement keeps the passage a free from all liability to silt up or become incrusted with deposit.

In order to assist the vacuum and make it more complete by insuring the absolute discharge of all air, the herein-described arrangement of air-release valve is devised, the action of which first admits contained air to the casing through valve d² and allows its escape through orifice d'.

If, from any cause, the feeder does not act, or should the supply of water fail, steam enters the discharge-pipe C and allows water contained therein, and also water contained in the delivery-pipe K, up to the trap p, and in the

whistle-tube Q (which is constantly full of water when the feeder is at work, thereby keeping the fusible plug cool) to fall into the boiler. Steam then reaches the fusible plug and melts it, and the whistle sounds. The steam continues to blow through the whistle until the cause of stoppage is attended to, the said steam being unable to reach the feeder on account of the water contained in the trap p. This action takes place immediately, and before the water can go down half an inch below its proper level in the boiler.

What I claim as my invention is—

1. In a boiler-feeder, the combination, with the main vessel and passages and steam-pipe, of a single acting steam-valve, B, weighted in proportion to the area of its seat and having a weight, b, acting upon it of calculated diameter, or a ring, b^2 , around it of calculated area, and a clearance-space, b^3 , for automatically closing the valve when the required velocity of steam is attained, substantially as and for the purposes set forth.

2. In a boiler-feeder, the combination, with the main vessel and passages and steam pipe and valve adapted to remain open until a certain velocity is attained, of an enlarged suction and delivery chamber, G, for insuring expansion and increased velocity of steam, so as to operate the steam-valve, substantially as set forth.

3. In an automatic boiler-feeder, the combination, with the main vessel, steam pipe and valve, and enlarged chamber, of a separate chamber directly connected with the water in the boiler, provided with an injection-valve constructed as specified, fitted with ascension pipe adapted to inject water to condense steam and form vacuum, substantially as set forth.

4. In a boiler-feeder provided with a vertical passage between the main vessel and the steam-valve and means for obtaining vacuum,

a tube adapted to slide automatically for a fixed distance within the passage at each action of the apparatus and fitted internally with a movable spindle arranged to move after it for the purpose of preventing deposit in the passage, substantially as set forth.

5. In a boiler-feeder such as is specified, the combination, with the main vessel, passages, and steam pipe and valve operating as described, of a casing containing a float fitted with pin-valves for automatically controlling air-escape orifices, substantially as and for the purposes set forth.

6. An automatic boiler-feeder constructed and arranged and operating as hereinbefore described and illustrated by the accompanying drawings.

7. The combination, with an automatic boiler-feeder constructed, arranged, and operating as hereinbefore set forth, of its connections to a boiler, consisting of the steam-pipe C, and its extension to about water-level c', fitted concentrically within the delivery-pipe K, provided with trap-bend, such as p, all arranged substantially as and for the purposes set forth.

8. The discharge-pipe C', passing concentrically into and down a delivery-pipe, K, to or about to the working-level of the water within the boiler, provided with trap-bend p, in combination with an alarm-whistle, Q, with steam-pipe adapted to be constantly full of water when the feeder is at work, and a fusible plug contained therein, substantially as and for the purposes set forth.

In testimony whereof I have signed my name to this specification in the presence of two subscribing witnesses.

ALFRED MAYHEW.
